UNITED STATES PATENT OFFICE.

FRANK E. MORGAN, OF NEW HAVEN, CONNECTICUT, ASSIGNOR TO THE NEW HAVEN CLOCK COMPANY, OF SAME PLACE.

ELECTRIC INDICATOR.

SPECIFICATION forming part of Letters Patent No. 414,868, dated November 12, 1889.

Application filed April 5, 1889. Serial No. 306,107. (No model.)

To all whom it may concern:

Be it known that I, FRANK EDWARD MORGAN, residing at New Haven, in the county of New Haven and State of Connecticut, have 5 invented certain new and useful Improvements in Electric Indicators; and I do declare the following to be a full, clear, and exact description of the same, reference being had to the accompanying drawings, which form a 10 part of this specification.

My invention relates to an improvement in variable signal-transmitters for that class of indicating or annunciating apparatus in which a series of such transmitters located at 15 sub-stations are combined with a receiver located at a receiving-station and provided with a transmitter-indicator to locate the respective transmitters and a signal-indicator to reproduce the signals thereof, the object of the 20 present invention being to produce a transmitter having convenient mechanism for breaking the circuit through it while it is being set and for protecting it from being accidentally operated.

25 With these ends in view my invention consists in a transmitter having certain details of construction and combinations of parts, as will be hereinafter described, and pointed out in the claims.

30 In the accompanying drawings, Figure 1 is a view in front elevation of one form which a transmitter embodying my invention may assume. Fig. 2 is a view thereof with the ring and hasp removed. Fig. 3 is a sectional view of the 35 device on the line *a b* of Fig. 1. Fig. 4 is a sectional view of the device on the line *c d* of Fig. 2. Fig. 5 is a view in front elevation of such a receiver as transmitters made in accordance with my invention may be combined 40 with; and Fig. 6 is a view in the nature of a diagram, and showing the contact-buttons, the contact-ring, and the circuit-closer of the said receiver, the hasp-connections of a transmitter, the main-line wire between the transmitter and the receiver, and the battery in 45 such line.

As herein shown, the transmitter is provided with a pointer *A*, forming the indicator of the device, a metallic disk *B*, having a 50 small rubber block *C* set into its periphery

and forming the circuit-controller of the instrument, a magnet *D*, which restores the pointer to its position of rest and operates the circuit-controller to break the circuit, and a circuit-interrupter constituting my present 55 invention and here taking the form of a hasp *E*. The said pointer *A* is arranged to be swept over a dial *F*, having a circular series of signals or wants printed upon it, and is rigidly secured to an arbor *G*, mounted in 60 frame-plates *H H* and projecting centrally through the dial and through a glass *I*, covering the same, the projecting end of the arbor being provided with a knurled thumb-nut *J* for rotating the arbor to set the pointer, 65 which is located between the dial and glass. The circuit-controller is also mounted upon the said arbor in position to break the circuit when the pointer is in its zero position or when it points to a star on the dial. The 70 said magnet *D* operates to restore the pointer to its position of rest and to actuate the circuit-controller to break the circuit through a star-wheel *K*, rigidly secured to the arbor having the same number of teeth that the dial 75 has signals or wants and actuated by an anchor-shaped pallet *L*, carrying an armature *M*, arranged to be attracted and released by the magnet, one end of the coil whereof is connected with a conductor *N*, branched to lead 80 to two contact-fingers *O O*, secured to a rubber block *P*, and so insulated from the instrument and engaging with the periphery of the circuit-controller disk *B*, before mentioned. The other end of the magnet-coil is connected 85 by a conductor *Q* with a main-line wire *R*, which includes all of the transmitters in the series, a battery *S*, and a receiver, one form of which is shown by Fig. 5 of the drawings. From the said fingers the current flows 90 through the disk *B* to the arbor *G*, thence through the plates *H H* to the back *T* of the instrument, thence to the ring *U* thereof, and thence to the circuit-interrupting hasp *E*, which is hinged to a strap or re-enforce *V* attached to the ring. The said hasp *E*, as herein 95 shown, is made from sheet metal having midway of its ends an enlargement *W*, which is struck up to form a boss *X*, to close around and yet clear the knurled thumb-nut *J*, which 100

it guards. The opposite end of the hasp is provided with an operating - button Y, by which it is opened and closed, and with a contact-finger Z, forming a part of a wire A', employed for stiffening the hasp throughout its length. When the hasp is closed, the said finger engages with a contact-spring B', insulated from the instrument in a recessed rubber block C', secured to the ring and connected with a binding-post D', also mounted in the said recessed block and receiving a special wire E', leading from the transmitter to the receiver.

It will be seen that under the construction described the circuit through the main line and including the battery, the receiver, and the transmitter, is closed through to the disk B and the fingers O O, when the hasp is closed, and loops the transmitter-frame, and hence the disk B, into the circuit. It will be equally clear that when the hasp is open and the connection between its finger and the spring B' is broken the transmitter will be cut out of circuit-connection with the battery and receiver, and that the circuit-controller, and hence the pointer, may be freely moved without closing a circuit through the receiver; but as soon as the hasp is closed again the transmitter will be cut into the circuit. The hasp, therefore, forms a circuit-interrupter, whereby the transmitter may be cut out of the main circuit and into the same at pleasure, so that the required time for setting the transmitter may be taken without any reference to the receiver. The hasp has also the important function of preventing access to the thumb-nut when the instrument is in the circuit, and thus avoiding the confusion which might result on account of a guest changing his mind after once setting the pointer, which he cannot reach without opening the hasp and cutting the instrument out of circuit. The hasp also prevents the thumb-nut from being accidentally moved when the device is not in use.

The receiver, as shown by Fig. 5 of the drawings, is provided with a case F', a dial G', a pointer H', forming a transmitter-indicator, a pointer I', forming a signal-indicator, and a resetting-manual J', the pointer H' being attached to a spindle K' and the pointer I' being secured to a sleeve L', mounted upon the said spindle, which is rotated by a train, (not shown,) while the said sleeve is rotated by an independent train (not shown) automatically released by the closing of a circuit through the receiver and one of the transmitters. The said dial G' is provided with a circular series of numbers, specified by the pointer H', and each indicating a transmitter, and with a similar series of signals located within the number-series, specified by the short pointer I', and corresponding to the signals or wants on the transmitter-dials, except in being reversely arranged.

The necessity of providing for time for setting the transmitters may be shown in con-

nection with Fig. 6 of the drawings, which shows a part of the mechanism located within the case F'. The contact-buttons M', arranged in a circular series, respectively, constitute the special wire, and therefore the receiver-terminals of the several transmitters. A circuit-closer N' and a brush O', both mounted on an insulated rotatable arm P', acting in unison with the pointer H', sweep over the said terminals and a ring Q', which is located in the main circuit. The closing of a circuit in one of the transmitters at once closes the main circuit through to the particular button forming the receiver-terminal of the transmitter calling and starts the circuit-closer in search of that button. As soon as the button is found the connections of the main circuit are completed and the circuit-closer is stopped and locked with the pointer H' (connected with it,) standing over the number on the dial G' representing the transmitter calling. Now, as soon as the circuit-closer stops, the receiver operates to reproduce the signal over which the indicator of the transmitter stood when the main circuit was closed through the said button and circuit-closer; but the closing of this circuit may take place almost at once after the circuit has been closed in the transmitter, and even before time has been given to sweep the transmitter-indicator over the dial to the signal thereon, which it is desired to reproduce in the receiver. Suppose, for instance, that the receiver has been reset to leave the circuit-closer in the position in which it is shown in the drawings, and that the next transmitter operated is connected with the contact - button x, which is the next button to be engaged by the circuit-closer in its rotation in the direction of the arrow. In such case the circuit-closer would be started and stopped and the receiver started to reproduce a signal before the indicator in the transmitter could be moved farther than one or two points from its zero position and before the guest could place it rightly. It becomes necessary, then, to provide time in which to set the transmitter, and I have provided for this time by a circuit-interrupter, forming a part of and attached to the transmitter and cutting the same in and out of the main circuit as it is operated.

I do not confine myself to the particular form of circuit-interrupter shown and described, or to using my invention with the form of receiver illustrated. I would therefore have it understood that I do not limit myself to the exact construction shown and described, but hold myself at liberty to make such changes and alterations as fairly fall within the spirit and scope of my invention.

Having fully described my invention, what I claim as new, and desire to secure by Letters Patent, is—

1. A variable signal - transmitter having a dial, an indicator, a magnet, a circuit-controller, and a circuit-interrupter hinged to the

instrument, so as to be swung over and away from the dial and cutting the said circuit-controller into and out of an electric circuit, substantially as set forth.

- 5 2. A variable signal-transmitter having a dial, an indicator, a magnet, a circuit-controller, an insulated contact-finger located at one side of the said dial, and a circuit-interrupter hinged on the other side of the dial 10 from the said finger, with which it is engaged and disengaged to cut the circuit-controller into and out of an electric circuit, the said circuit-interrupter swinging over and away from the dial, substantially as set forth.
- 15 3. A variable signal-transmitter having an indicator, a magnet, a circuit-controller, and a hinged circuit-interrupter, forming a part 20 of the instrument, cutting the same into and out of an electric circuit, and constituting a guard for the indicator, substantially as set forth.

- 25 4. A variable signal-transmitter having an indicator, an arbor on which the same is mounted, an exposed thumb-nut secured to the arbor for use in operating the indicator, a magnet, a circuit-controller, a hasp hinged

to the instrument and adapted to fit over the nut and form a guard for it, and a contact-finger insulated from the instrument and engaged by the finger for cutting the instrument into and out of an electric circuit, substantially as set forth. 30

5. The combination, with a signal-transmitter having a signal-indicator, a circuit-controller, a magnet for operating the said indicator and controller, and a circuit-interrupter for cutting the transmitter into and out of an electric circuit, of a receiver having a transmitter-indicator to specify the transmitter and a signal-indicator to reproduce 40 the signals thereof, the said circuit-interrupter being hinged to the transmitter and forming a guard for the indicator thereof, substantially as set forth. 35

In testimony whereof I have signed this 45 specification in the presence of two subscribing witnesses.

FRANK E. MORGAN.
